UNITED STATES PATENT OFFICE.

CARL CHRISTIAN HANSEN, OF FREDERIKSBERG, DENMARK.

SHOE-STITCHING MACHINE.

1,204,867.

Specification of Letters Patent. Patented Nov. 14, 1916.

Application filed August 27, 1914. Serial No. 858,861.

To all whom it may concern:

Be it known that I, CARL CHRISTIAN HANSEN, of No. 8 Aeroevej, Frederiksberg, near Copenhagen, in the Kingdom of Denmark, have invented certain new and useful Improvements in Shoe-Stitching Machines; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

Shoe stitching machines are already known in which there are used a curved, hook-shaped needle and a likewise curved awl, which turns around the same axle as the needle, and in which the shuttle which catches the thread is disposed above the table. In shoe stitching machines of this kind, the sole is held fast between the table below and a presser-foot above, the latter following the grooving in the sole. These holding devices must be adjusted vertically in relation to each other in accordance with the thickness of the work. Now since this adjustment takes place vertically, and since both needle and awl turn around the same axle, it frequently happens that the needle strikes against one of the holding pieces and breaks.

It has been especially difficult to obtain a sufficiently secure guiding of the rest, so that as the wear takes place, it will often happen that the needle or the awl is broken.

In known machines of this kind the rest consists of a cylindrical portion or bushing through which the axle, common to the needle and awl, is passed and a laterally projecting portion in which the hole is formed for the passage of the needle and the awl. This causes an oblique influence and consequently an uneven wear and pressure on the rest. According to the present invention, this drawback is prevented by using a rest which has two journals on the axle, between which journals a hole is formed for the passage of the needle and awl.

A form of construction of this invention is shown on the drawing, in which—

Figure 1 is a top view of the machine, Fig. 2 is a front view of the same, Fig. 3 shows the parts which cause the movement of the needle, Fig. 4 shows the members that cause the movement of the awl, Fig. 5 is a

front view of the shuttle, Fig. 6 is a section of the shuttle, Fig. 7 is the mechanism by means of which the thread is pulled, and Fig. 8 is the carrying and releasing mechanism.

The main axle 2 of the machine has its bearings in the machine-frame 1, Figs. 1 and 2. This axle is turned in a known manner by means of a fly-wheel, or the like, not shown on the drawing, and carries an eccentric cam 3, Figs. 1 and 2, upon which rests a bar 4 pivoted at one end on a pin 5, and carrying on its other end a rack 4^a which is reciprocated up and down as the axle 2 rotates. The rack 4^a meshes with a pinion 6, which moves a shuttle-carrier 7, which is disposed in the shuttle-bearing 8 and carries the shuttle 9 with shuttle-point 10 (see Figs. 5 and 6). The main axle 2 also carries a cam 11, which has lateral undulating edges 12, between which there moves a roller 13, disposed on the lower side of a rod 14, one end of which is connected to an axle 15, having its bearings in the frame, in such a manner that it can be moved laterally and reciprocated longitudinally (see Fig. 1).

The lateral movement of the rod is caused by the undulating movement of the roller 13 between the edges 12 of the cam 11, and the reciprocating movement is caused by a roller 16 (see Fig. 7), which is disposed on the side of the cam 11, and which presses against a peculiarly-shaped rod 17 pivoted on a pin 18 and provided with a semi-cylindrical projection 19, which acts on the one end of the rod 14. At its opposite end the rod 14 carries a loop-eye 20, which thus, in the manner above described, is given both a lateral and a reciprocating movement. On the pin 18 is also pivotally disposed a take-up rod 21 with a knee 22 and, in its free end, an eye 23, through which the thread is carried to the loop-eye 20.

The axle 2 further carries a disk 25, Fig. 3 having a roller 26 on its side adapted to actuate the take up rod 21 and a curved projection 27 on its edge. In the other side of the disk 25 is disposed a curved groove 28, in which can move a roller 29, attached to a cog-segment 30 pivoted on the axle 15. The cog-segment 30 meshes with another cog-segment 31 firmly fixed on the axle 32 in common for both needle and awl, and carrying the needle 33. On the axle 32 is disposed the needle-protector 34, which is actuated by a spring 35, disposed on the cog-

segment 31, in such a manner that it only follows the movement of the needle a short distance downward. The curved projection 27 on the disk 25 acts against the end of a 5 rod 36 (Fig. 1) disposed between the needle 33 and the shuttle 9, which rod is surrounded by a spiral spring pressing it against the disk 25. Thus the rod 36 is given a reciprocating movement. The other end of the rod 10 36 is formed like a hook-shaped point 37 extending forward in front of the needle 33. Furthermore the axle 2 carries a disk 38 (Fig. 4) which has a groove 39 in which can move a roller 40 disposed on a cog-seg- 15 ment 41 pivoted on the axle 15. The cog-segment 41 meshes with the cog-segment 42, pivoted on the axle 32 and carries the awl 43. Finally the main-axle 2 carries a disk 44 (Figs. 1, 2 and 8), which has lateral, un- 20 dulating edges 45, between which moves a roller 46, disposed on the lower side of a carrier-rod 47 capable of turning in a horizontal plane on a pivot post 48 in such a manner that the fork-shaped, free end 49 of 25 the rod 47, grasps around the cog-segment 42, and gives the latter a lateral movement (see Fig. 1). The disk 44 carries on its side a roller 50 which, as the disk turns, moves a suitably disposed pawl 51 in such a manner that it will engage teeth on a toothed sector 52, pivoted on a pin 53 which has its bearing in the machine-frame 1 and actuate the sector against the pull of a spring 54. The sector 52 is provided with a pin 55 30 which travels in a slit 56 in the long arm of a lever 57 fulcrumed on the axle 32 the other arm of said lever forming a rest 57^a. As shown in Figs. 1 and 2, this rest has the form of a loop journaled on the shaft 32 on 35 each side of the path of the needle and awl, the loop portion being formed with a hole, as shown in Fig. 3, to permit the passage of the needle and awl through the rest. This overcomes the before-mentioned oblique influence so that the rest is easily moved and 40 is more durable. Above the rest 57 a presser-foot 58 is stationarily disposed on the machine-frame 1.

The machine works in the following manner: The sole is placed between the presser-foot 58 and the rest 57^a, after which the machine is started. The awl 43 is then driven up through the sole by the cog-segments 41, 42 through the action of the cam 39 on roller 40. Then the rest 57 is lowered by the action of the roller 50 on the pawl 51, the toothed sector 52 being rocked so as to raise

the lever arm 57 against the action of the spring 54, after which the boot is carried forward by means of the carrier-rod 47 moving the cog-segment 42 and the awl 43 to the left until it comes under the needle 33, after which both the awl and needle are given a downward movement. During this movement the pawl operates to lock the segment against movement so that the rest 57^a cannot be depressed by the withdrawal of the awl from the sole. At this moment the loop-eye 20 carries the thread around the needle 33, which then recedes and takes the 60 thread with it through the sole. Now the hook 37 carries the fast end of the thread forward, so that the point 10 of the shuttle can reliably grasp it and pass it around the shuttle 9, so that it will take with it the underthread after which the take-up rod 21, whose knee 22 is actuated by the roller 26, ties the threads in the leather. The thread from a spool, not shown, passes through a tension device of well known form which 70 consists of two disks 59 and 60 that are pressed together by means of a spring 61, the tension of which may be adjusted by means of a nut 62 on the end of a spindle 63 surrounded by the spring and on which 75 the disks are mounted. After passing through the tension device said thread passes through the eye 23 and then through the eye 20 to the needle.

I claim:

In a shoe stitching machine, the combination with a curved needle and a curved awl pivoted on a common axle, and mechanism for advancing and retracting said needle and awl; of a fixed presser foot coöperating with the awl, a sole rest comprising a two armed lever fulcrumed on the axle one of said arms being provided with a longitudinal slot and projecting beneath the presser foot, a sector pivotally mounted on the machine frame, a rack on said sector, a pin on one end of the sector engaging said slot in the other arm of the lever, a pawl arranged to depress the other end of the sector and to engage said rack to lock the sector in position, and means to actuate the pawl.

In testimony that I claim the foregoing as my invention, I have signed my name in presence of two subscribing witnesses.

CARL CHRISTIAN HANSEN.
